UNITED STATES PATENT OFFICE.

CARL E. SKOOG, OF PROVIDENCE, RHODE ISLAND, ASSIGNOR TO PARKS BROS. & ROGERS, INC., OF PROVIDENCE, RHODE ISLAND, A CORPORATION OF RHODE ISLAND.

SEPARABLE-LINK CUFF-BUTTON.

1,250,039.

Specification of Letters Patent.

Patented Dec. 11, 1917.

Application filed March 14, 1917. Serial No. 154,694.

To all whom it may concern:

Be it known that I, CARL E. SKOOG, a citizen of the United States, and a resident of Providence, in the county of Providence and State of Rhode Island, have invented a new and Improved Separable-Link Cuff-Button, of which the following is a full, clear, and exact description.

Among the principal objects which the present invention has in view are: To increase the service period of buttons of the character mentioned; to adapt a button of the character mentioned of one-piece construction to the needs of an auxiliary spring grip; and to avoid wear on garments with which buttons of the character mentioned are associated.

Drawings.

Figure 1 is a longitudinal section of a tubular, centrally-perforated cup having loosely installed therein a retaining spring and a supporting perforated disk therefor;

Fig. 2 is a side view of the above-mentioned disk;

Fig. 3 is a detail view on an enlarged scale showing the above-mentioned cup, disk and spring after the cup has been shaped and longitudinally contracted;

Fig. 4 is a cross section on an enlarged scale, the section being taken as on the line 4—4 in Fig. 3;

Fig. 5 is an edge view of link buttons, the female member being shown in section and the male member in full lines, the said members being constructed and arranged in accordance with the present invention;

Fig. 6 shows a modified form of a spring employed in the present button;

Fig. 7 is a further modification of the same.

Description.

As seen in the drawings, cuff buttons when constructed and arranged in accordance with the present invention have a shank wherein the head 10, flange 11, and throat 12 are constructed from the same piece of metal. The single piece of metal referred to is shown in Fig. 1 of the drawings, where the metal is shaped to form a cylindrical cup 13, the bottom of which is partially closed by the dome 14. At any stage in the proceedings of forming the metal to the shape as shown in Fig. 1, a central opening 15 is made in the dome 14. The opening 15

is sufficiently large to permit the free passage therethrough of a throated nib 16, which is extended from the head 17 of the male member.

To hold the nib 16 in service a circular spring 18 having separable gripping ends 19 is disposed in the bottom of the cup 13, as shown best in Fig. 1 of the drawings. To hold the spring 18, a disk 20 is also deposited in the cup 13 above the spring 18. The disk 20, as shown best in Fig. 2 of the drawings is provided with a perforation 21 centrally disposed therein also capable of passing the nib 16.

After the spring 18 and disk 20 have been disposed as described in the cup 13, the throat 12 is formed by contracting the sides of the cup 13, while pressing the dome 14 and flange 11 toward each other. This operation is continued until the female member of the link button is shaped in cross section as shown in Fig. 3 of the drawings, where it will be noted that the disk 20 is held firmly between the contracted annular edge of the head 10 of the female member.

The male member of the link button has a base flange 11, neck portion 12, and head 17 shaped in the same manner as the flange 11, throat 12, and head 10 of the female member. Instead of the opening 15, the head 17 has the throated protected nib 16. The nib 16 has a contracted throat 22, which is engaged in service by the gripping ends 19 of the spring 18. The sides of the throat 22 are so shaped that the nib 16 is pressed through and withdrawn from between the gripping ends 19 of the spring 18. When pressed through said ends 19, they operate to hold the nib 16 in position, where the edge of the hole 15 bears lightly on the adjacent surface of the head 17.

In the modified form shown in Fig. 6 of the drawings, a wire spring having a bow 23 is so folded as to have parallel extensions 24 which engage upon the area of the openings 15 in the head 10 and disk 20.

In the modified form of the spring shown in Fig. 7 of the drawings, a flat disk 25 constructed of resilient material is punched to provide sectional yielding tongues 26 converging to a central opening 27, the diameter whereof is slightly less than the nib 16 of the male member.

Operation of all of the forms is substantially the same.

While certain preferred and modified forms have been disclosed herein, it will be understood that the invention is not limited to these forms, and that other modifications 5 may be employed with desirable effect and come within the scope of the present claim.

Claim.

A cuff button having an integrally formed 10 male member provided with a base flange, throat, head and threated nib extended therefrom; an integrally formed female

member having a base flange, throat, and centrally perforated head adapted to engage said nib; means for holding said nib 15 in the head of said female member, said means embodying a contractible gripping spring loosely mounted in the head of said female member; and means for supporting said spring, said means embodying a centrally perforated disk mounted in the head 20 of said female member.

CARL E. SKOOG.
